SHOE SOLE ATTACHING

Frederick V. Nugent, Abington, Mass., assignor to
 United Shoe Machinery Corporation, Flemington, N. J., a corporation of New Jersey

Application January 10, 1947, Serial No. 721,342

14 Claims. (Cl. 12—33)

1

This invention relates to shoe sole attaching and more particularly to the cohesive attachment of soles to shoes by fusion. The invention is particularly useful in the attachment of soles to shoes in which the attaching faces of the shoe parts are of thermoplastic materials. Thus, the attaching faces of each may be coated with a layer of thermoplastic material or one or both of the shoe parts may be composed entirely of thermoplastic material. It will further be understood that the invention is applicable to the manufacture of shoes or to the attachment of soles in repairing shoes.

Apparatus heretofore employed in attaching soles to shoes by fusion contemplates the simultaneous all-over heating of the attaching faces of the shoe parts to soften the adhesive thereon followed by the pressing together of the shoe parts. This is accomplished in one form of apparatus as disclosed by Letters Patent of the United States No. 2,342,725, granted February 29, 1944, on an application filed in the name of Ernest A. Crepeau, by introducing a radiant heater between the shoe parts while the shoe parts are held in spaced relation, permitting the heater to remain therebetween until the adhesive on the shoe parts is sufficiently softened, and then withdrawing it and bringing the shoe parts together under pressure to attach the sole to the shoe bottom. Another form of apparatus as shown in Letters Patent of the United States No. 2,417,065, granted March 11, 1947, on an application filed in the names of Paul H. Dixon and Joseph R. Ioannilli, utilizes a conduction heater held in contact with the shoe parts throughout the extent of their attaching faces until the adhesive thereon is softened whereupon the heater is removed from between the shoe parts and pressure is applied to attach the soles to the shoe bottom.

It is an object of the present invention to provide an improved method for attaching soles to shoes and an apparatus for carrying out the method which is of simplified construction and capable of use on shoes of varying sizes and styles without the necessity of making any complicated adjustments in the apparatus or changing any parts thereof. This is accomplished in accordance with a feature of the invention by assembling the sole and shoe, progressively heating the attaching faces thereof around the margin of the shoe and progressively applying attaching pressure to the sole immediately following the heating thereof. As illustrated herein the heating is effected by means of a heating blade arranged to be positioned between the marginal portions of

2

the sole and shoe, the shoe being moved relatively to the blade so that the marginal portions are softened progressively. Pressure-applying elements are located immediately to the rear of the heating blade in the direction of feed of the work so that each portion of the sole and shoe is pressed together immediately after their marginal portions have been heated.

For operating on welt shoes in accordance with a further feature of the invention the feeding of the work is accomplished by means of a pair of coacting rolls one of which is driven and which rolls also serve progressively to apply pressure to the sole and welt. The heating blade is located immediately in advance of these rolls so that the pressure upon each part of the sole and welt is applied immediately after the activation of the thermoplastic materials is completed. For operating upon shoes of the type in which the upper is lasted over the insole in substantial parallelism throughout the lasting margin with the bottom of the shoe, frequently designated as "flat-lasted" shoes, the pressure may be applied by a reciprocating hammer cooperating with an anvil upon which the shoe may be supported, the feeding of the shoe being effected by the operator between successive blows of the hammer.

The above and other features of the invention including various details of construction and novel combinations of parts will now be described by reference to the accompanying drawings and pointed out in the claims.

In the drawings,

Fig. 1 is a side elevation partly in section of one form of machine by which the method may be practiced, the work-engaging elements being shown in operative relation to a shoe;

Fig. 2 is a plan view of the work-engaging elements in operative relation to a shoe;

Fig. 3 is a side elevation partly in section of another form of apparatus by which the method may be practiced;

Fig. 4 is a side elevation on a larger scale of the work-engaging elements of the apparatus shown in Fig. 3 in operative relation to a shoe, and

Fig. 5 is a front elevation, partly in section, of the work-engaging elements in operative relation to a shoe.

The machine illustrated in Figs. 1 and 2 is designed for operation on welt shoes in which the attaching surfaces of the welt and sole are of thermoplastic materials which may be activated or softened by heat and fused together by the subsequent application of pressure. The welt is sup-

ported with the shoe in inverted position by a roll 10 with which cooperates a driven roll 12 engageable with the outsole opposite to the zone of engagement of the roll 10. The roll 12, in cooperation with the roll 10, acts to feed the shoe in the direction of the arrow in Fig. 2. Located immediately in advance of the zone of pressure between the rolls 10 and 12 is a heater in the form of a thin metallic blade 14 positioned to lie between the sole and welt to soften the thermoplastic materials immediately prior to the application of pressure by the rolls 10 and 12.

It should be understood that either the welt or the outsole or both may consist entirely of thermoplastic materials or may be provided with a coating of thermoplastic material in the form of a cement which has been previously applied in liquid form and allowed to harden.

The roll 10 by which the welt is supported, has a supporting surface 16 formed at an acute angle with the under surface 18 of the roll 10 so that the roll at its periphery is sufficiently thin to enter the welt crease of the shoe and to provide adequate support for the welt throughout substantially its entire width. The roll 10 is carried by a shaft 20 rotatable in bearings 22 which are supported by a bracket 24. This bracket is secured by screws 26 to a vertical support 28 having a horizontal portion 30 by which it is attached to a suitable table or other supporting member 32.

The roll 12 is secured to the threaded end of a shaft 34 journaled in bushings 36 in opposite ends of a sleeve 38. This sleeve is carried by a slide 40 movable vertically in the support 28. For turning the shaft 34 it is provided at the end opposite the roll 12 with a pulley 42 by which it may be connected to a suitable source of power. A spring 44 interposed between the sleeve 38 and the upper end of the support 28 urges the sleeve and with it the roll 12 upwardly into a position determined by the engagement of a pin 46 in the lower end of the slide with the bottom of the support. When the roll 12 is moved into this position it is spaced sufficiently from the roll 10 and the blade 14 to permit the work to be inserted readily between the rolls with the blade lying between the welt and outsole. The pin 46 provides a connection between the slide 40 and a pull rod 48 which may be connected to a treadle (not shown) by which the slide, the sleeve 38, and the roll 12 may be moved downwardly by the operator against the action of the spring 44 so that the roll 12 engages the outsole and in cooperation with the roll 10 feeds the work and presses the welt and outsole together.

The heating blade 14 by which the thermoplastic materials at the attaching faces of the welt and outsole are activated is formed of a thin flat metallic resistance material of U shape in plan as shown in Fig. 2, the cross sectional areas of the blade being preferably uniform throughout so that the blade will have a uniform resistance and consequently a uniform heating effect when connected to a source of electrical energy. This blade is located just in advance of the zone of contact of the rolls 10 and 12 when viewed in the direction of feed of the work so that the thermoplastic materials are activated immediately prior to the action of the rolls on the welt and outsole. The ends of the blade 14 are connected to flexible conductor bars 50, 52 which are in turn connected by screws 54 to a block 56 of suitable electrical insulating material. The block 56 is secured by a screw 57 to the bracket 75

24 and insulates the machine from the conductor bars. By connecting the ends of the conductor bars to a source of electrical energy, current will pass therethrough and through the heating blade 14 which, because of its relatively high resistance with respect to the conductor bars, will be heated to a sufficiently high degree to activate the thermoplastic materials at the attaching faces of the welt and outsole very rapidly. It will be understood that the blade 14 and the conductor bars 50, 52 are sufficiently flexible so that the blade may accommodate itself readily to variations in the thickness of the welt.

In carrying out the method with the apparatus disclosed in Figs. 1 and 2, the outsole O will be first spotted on the bottom of the shoe S in any suitable manner after which one end of the welt W will be placed on the roll 10 with the blade 14 between the welt and the outsole at substantially the same location. The roll 12 will now be moved downwardly through the pull rod 48 and will engage the outsole opposite to the roll 10 whereupon the assembled shoe and outsole will be fed by the action of the rolls and guided by the operator. During this feeding movement the blade 14 activates the thermoplastic materials at the attaching faces of the sole and welt and on the inseam if this has also been provided with thermoplastic material. Because the shoe and sole are being fed by the rolls the blade 14 acts to activate successive portions of the shoe parts around the margin of the shoe bottom immediately following which the rolls 10 and 12 press the sole and welt together before the cement has had an opportunity to become hardened by cooling.

The form of invention illustrated in Figs. 3, 4 and 5 is adapted more particularly in practicing the method of the invention when attaching a sole to a shoe of the flat lasted type. In this form of apparatus a heating blade 60 which may be similar to the blade 14 of Figs. 1 and 2 is provided for insertion between an outsole O and the overlasted margin of an upper u each of which parts may be formed at their attaching faces of thermoplastic materials. The other work-engaging elements consist of a horn 62 engageable with the foot-engaging face of the insole i, it being understood that if a new shoe is being operated up the last is withdrawn prior to the sole-attaching operation. The top face of the horn which is flat rests against the insole at its marginal portion and directly opposite the horn is a hammer 64 which is rapidly reciprocated to cause a localized portion of the outsole and the overlasted portion of the upper to be forced together causing the thermoplastic materials at their attaching faces to become fused together after they have been activated by the heating blade 60. This heating blade will preferably be located just outside the zone of pressure between the horn and the hammer as shown in Fig. 5, although in this case, since the feeding of the shoe and assembled outsole will take place between blows of the hammer, the blade 60 might overlap the zone of pressure between the hammer and horn.

The heating blade 60 is mounted for vertical adjustment to vary the space between it and the hammer 64 when the hammer is in its lowermost position thereby to accommodate outsoles of different thicknesses. For this purpose it is carried by a bracket 61 adjustably mounted by screws 63 passing through slots 65 in the bracket and threaded into a supporting frame 68. A second

bracket 68 secured to the frame carries an adjustable stop screw 71 engageable with the underside of the bracket 61 thereby to determine the heightwise position of the bracket on the supporting frame.

The hammer 64 is formed on the lower end of a plunger 66 mounted for vertical movements in the upper end of the supporting frame 68. Journaled in the upper end of this frame is a shaft 70 which is provided at its forward end with an eccentric pin 72 engageable with a transverse slot in the plunger 66 whereby the plunger is reciprocated upon rotation of the shaft. The other end of the shaft carries a pulley 74 connected by a belt 76 with a drive pulley 78 on the shaft of a motor 80 secured to the upper end of the frame 68. The pulley 74 is connected to the shaft 70 by a clutch 82 operated by a rod 84 connected to a treadle 86 pivoted at 88 to the base of the machine and urged upwardly by a spring 90. The clutch 82 may be of the type known as a pin clutch which when the rod 84 is depressed will cause the shaft 70 to be rotated continuously and when the rod 84 is raised will cause the shaft 70 to stop with the hammer 64 in raised position. A clutch of this type is disclosed in United States Letters Patent No. 958,293, granted May 17, 1910, on an application of T. G. Plant.

The horn 62 has a stem 94 mounted for vertical movement in the frame 68. This stem is hollow and contains a spring 96, the upper end of which rests against a disk 98 engaged by a screw 100 threaded in the horn 62. The lower end of the spring rests against the head of a stud 102 arranged to slide through a plug 104 threaded into the lower end of the stem 94. Connected to the stud 102 is a block 106 to which is pivoted at 108 a bell crank lever 109, one arm 110 of which is connected to a link 112, the lower end of which has a fixed bearing at 114. The other arm of the bell crank lever is connected to the treadle 86 by means of a yieldingly extensible link comprising a rod 116 pivoted to the treadle and a link 118 pivoted to the arm of the bell crank lever 109. The rod 116 passes freely through an offset 120 on the link 118. A tension spring 122 is confined on the rod 116 between the offset 120 and a nut on the upper end of the rod and is maintained under any desired initial tension by a nut 124 threaded on the rod and engaging the offset 120. Upon depression of the treadle 86 the toggle, composed of link 112 and arm 110, is straightened through the movement of the bell crank lever 109 to raise the horn 62 toward the hammer 64 supporting the work in the field of action of the hammer. The spring 96 which supports the horn may be set at any predetermined initial tension by turning the screw 100 and permits the work to yield when the pressure of the hammer exceeds the tension for which the spring is set. After the toggle is straightened the spring 122 permits further depression of the treadle to cause the clutch to be tripped and the hammer 64 operated.

In using this apparatus in carrying out the method with a flat lasted shoe an outsole will first be spotted on the bottom of the shoe and temporarily secured in any suitable manner after which the assembled shoe and outsole is presented to the machine. The outsole O is placed between the hammer 64 and the heating blade 60 whereupon the horn 62 is raised by depressing the treadle 86 thereby to support the shoe against the pressure to be exerted by the hammer. Upon further depression of the treadle the clutch 82 is engaged whereupon the hammer is reciprocated

rapidly and the work may be fed between successive blows of the hammer by the operator. Thus it will be seen that the thermoplastic attaching faces of the outsole and upper will be progressively activated by the blade 60 following which the outsole and upper are pressed together by the action of the hammer in cooperation with the horn 62. The marginal portions of the shoe are rapidly traversed in this manner and the attachment of the outsole is easily and quickly effected.

By the progressive method of attachment of the outsole to the shoe, whether the shoe be a flat lasted shoe or a welt shoe, the operation is completed rapidly without the necessity of employing complicated machinery and further without the necessity of making complicated adjustments in the machine or of changing parts to adapt the machines to varying sizes and styles of shoes. It will be further understood that the outsole and the welt or overlasted margin of the upper may be provided with any suitable heat-activated adhesive or any one or all of the parts may consist entirely of suitable thermoplastic material.

Having thus described the invention, what I claim as new and desire to secure by Letters Patent of the United States is:

1. A machine for attaching soles to shoes wherein the attaching faces of the soles and shoes are of thermoplastic materials, comprising a heater arranged progressively to activate the thermoplastic materials of a sole and shoe at their attaching faces around the margins thereof, and mechanism for progressively applying a localized attaching pressure to the sole and shoe immediately following the heating thereof.

2. That improvement in attaching soles to shoe bottoms in which the attaching faces of the shoe parts are of thermoplastic materials which comprises progressively heating successive portions of the attaching faces of a sole and shoe bottom to soften the thermoplastic materials while the sole is temporarily positioned on the shoe bottom, and applying pressure to each of said portions of the sole immediately following the heating thereof progressively to attach the sole to the shoe bottom.

3. That improvement in attaching soles to shoe bottoms in which the attaching faces of the shoe parts are of thermoplastic materials which comprises feeding an assembled sole and shoe past a device for heating the thermoplastic material of the attaching faces, and progressively applying attaching pressure to the sole and shoe immediately following the heating thereof.

4. A machine for attaching soles to shoes wherein the attaching faces of the soles and shoes are of thermoplastic materials, comprising a heating blade arranged for simultaneous contact with a localized portion of the attaching faces of an assembled sole and shoe and arranged upon relative movement between the sole and shoe and the blade progressively to activate the thermoplastic materials around the margin of the sole and shoe, and cooperating pressure elements for pressing each portion of the sole to the shoe bottom immediately following the heating thereof by said blade.

5. That improvement in attaching soles to shoe bottoms in which the attaching faces of the shoe parts are of thermoplastic materials which comprises positioning a heating blade between the marginal portions of an assembled sole and shoe, causing relative movement of the shoe and sole so that the heating blade progressively engages

the marginal portions to activate the thermoplastic materials, and simultaneously applying attaching pressure to the sole and shoe just rearwardly of the zone of heating by said blade.

6. That improvement in attaching soles to shoe bottoms in which the attaching faces of the shoe parts are of thermoplastic materials which comprises passing an assembled sole and shoe between a pair of pressure-applying devices, and applying activating heat to the attaching faces of the sole and shoe immediately in advance of said pressure-applying devices.

7. A machine for attaching soles to shoes wherein the attaching faces of the soles and shoes are of thermoplastic materials, comprising a heating blade arranged for simultaneous contact with a localized portion of the attaching faces of an assembled sole and shoe and arranged upon movement of the sole and shoe relatively to the blade progressively to activate the thermoplastic materials around the margin of the sole and shoe, and mechanism for feeding the sole and shoe relatively to said heating blade and for pressing the sole against the shoe bottom immediately following the heating thereof by said blade.

8. A machine for attaching soles to shoes wherein the attaching faces of the soles and shoes are of thermoplastic materials, comprising a heating blade arranged for engagement with a small marginal portion of the attaching faces of an assembled sole and shoe, means for supporting the assembled sole and shoe for the action of said heating blade, and means cooperating with said supporting means during feeding of the assembled shoe and sole relatively to said blade for pressing a portion of the sole immediately behind said blade against the shoe bottom.

9. A machine for attaching soles to shoes wherein the attaching faces of the soles and shoes are of thermoplastic materials, comprising a heating blade arranged for engagement with a small marginal portion of the attaching faces of an assembled sole and shoe, means for supporting the assembled sole and shoe for the action of said heating blade, and a driven roll cooperating with said supporting means to feed the assembled shoe and sole relatively to said blade and to press the sole against the shoe bottom, said roll and supporting means being located immediately behind said heating blade in the direction of feed of the assembled shoe and sole.

10. A machine for attaching soles to shoes wherein the attaching faces of the soles and shoes are of thermoplastic materials, comprising a heating blade arranged for engagement with a small marginal portion of the attaching faces of an

assembled sole and shoe, means for supporting the assembled sole and shoe for the action of said heating blade, and a reciprocating hammer cooperating with said supporting means during

5 feeding of the assembled shoe and sole relatively to said blade for exerting on the sole attaching pressure, said hammer and supporting means being located immediately behind the heating blade in the direction of feed of the assembled shoe and sole.

10 11. A machine for attaching soles to the bottoms of welt shoes wherein the attaching faces of the sole and welt are of thermoplastic materials, comprising a roll arranged to underlie and support the welt of an inverted shoe, a feed roll engageable with the marginal portion of an outsole cooperating with said supporting roll for feeding an assembled sole and shoe and for pressing the sole against said welt, and a heating member located immediately in advance of said rolls and arranged to activate the thermoplastic materials of the sole and welt immediately prior to the application of pressure thereto.

15 12. That improvement in attaching soles to the bottoms of welt shoes in which the attaching faces of the welt and sole are of thermoplastic materials which comprises passing the assembled sole and shoe between a pair of cooperating feed and pressure-applying rolls which engage the top 20 of the welt and the bottom of the sole, and applying activating heat to the attaching faces of the sole and welt immediately in advance of said rolls.

13. That improvement in attaching soles to shoe bottoms in which the attaching faces of the 25 shoe parts are of thermoplastic materials which comprises intermittently and progressively applying attaching pressure to the marginal portions of the sole and shoe, and heating successive portions of the attaching faces of the sole and shoe 30 immediately in advance of the application of pressure thereto.

14. A machine for attaching soles to the bottoms of welt shoes wherein the attaching faces of the sole and welt are of thermoplastic material 35 comprising a roll arranged to underlie and support the welt of an inverted shoe, a feed roll engageable with the marginal portion of an outsole cooperating with said supporting roll for feeding an assembled sole and shoe and for pressing the sole against said welt, and a flexible, thin, electrically-heated blade located immediately in advance of said rolls and arranged to activate the thermoplastic materials of the sole and welt immediately prior to the application of pressure thereto.
